CIGARETTE LIGHTER

Louis V. Aronson, Newark, N. J., assignor to Art Metal Works, Inc., Newark, N. J., a corporation of New Jersey

Application November 24, 1936, Serial No. 112,582

2 Claims. (Cl. 219—32)

The invention relates to a cigarette dispenser and lighter and has as an object the provision of a device whereby a cigarette may be secured in lighted condition by use of but one hand, being particularly useful in automobiles.

It is a further object of the invention to provide a device of the character referred to wherein the cigarette is lighted exteriorly of the supply receptacle.

10 It is a further object of the invention to provide a device of this character having an exceedingly simple form of puffing device.

Further objects of the invention will appear from the following description when read in connection with the accompanying drawing showing an illustrative embodiment of the invention, and wherein:—

Figure 1 is a front elevation;

Fig. 2 is a horizontal transverse section on line 2—2 of Figure 1;

Fig. 3 is a central vertical section on line 3—3 of Figure 1;

Fig. 4 is a perspective view of a mounting bracket, and

25 Fig. 5 is a detail section on line 5—5 of Fig. 3 upon an enlarged scale.

As shown the device comprises a receptacle 10 for receipt of a supply of cigarettes having a cover member 11 desirably in the form of an ash-receiving tray provided with an opening 13 in the top thereof.

To support and dispense the cigarettes from the receptacle 10 one at a time, there is shown a bottom member 14 hinged within the receptacle 35 upon an axis at 15 and with its forward free edge resting by gravity upon a dispensing member 16 which is pivoted upon an axis at 17 in the side walls of the casing. The member 16 comprises an arcuate portion 18 to receive a cigarette, which 40 cigarette when the member 16 is moved about its pivot will fall by gravity to be received by cradle members 19 placed below the bottom of the receptacle.

To prevent dispensing of more than one cigarette at a time, there is shown an arcuate extension 20 upon the member 16 which closes the space between the edge 21 of the member 14 and the front of the receptacle during the dispensing operation. A stop member 22 is shown secured to 50 the lower edge of the arcuate portion 20 upon which the member rests in its normal position and to which position the dispensing member is returned by a spring 23, Figure 1, coiled about the supporting shaft of the member 16.

55 The said shaft is desirably square and secured

to the dispensing member 16 as by solder and for producing a dispensing motion a finger lever 24 is shown in Figure 1 as secured rigidly to the end of the shaft exteriorly of the receptacle.

To ignite a cigarette lying upon the cradle 5 members 19, there is shown a cup member 25 supported by a pair of spring strips 26 and 27. One end of each of the strips 26, 27 is secured to the receptacle and both insulated therefrom as by insulation block 28. One of the strips as 26 in 10 the form shown is electrically connected to the conductor wire 29 and the said strip is in electrical connection with the screw member 30 by which the ignition member is fastened to the spring members 26, 27, which screw member is 15 insulated from the metallic cup member 25.

Within the cup member 25 there is shown a coiled resistance wire 31 which is electrically connected to the member 30 at one end and is grounded upon the cup member at its remaining 20 end. The spring 27 is in electrical connection with the cup member 25 but insulated from the spring 26 as by mica insulation 32. Fixed upon the casing 10 there is a contact 33 by which the spring 21 is grounded upon the metallic wall 25 of the receptacle which in turn is grounded upon the frame of an automobile when the device is mounted thereon.

At the opposite end of the cradle there is shown a button 34 perforated at its center as at 35 and 30 rigidly secured in a recess or opening surrounded by a downwardly extending portion of the wall of the receptacle. A groove for this connection is shown at 36.

Rigidly secured to the button 34 is a cylinder 35 37 containing a piston 38 normally pressed by spring 39 to the outer end of the cylinder. A button 40 is shown secured to the piston rod 41.

With a cigarette lying in the cradle 19, the electrical insulation button 42 may be pressed as by 40 an index finger to impinge upon the end of the cigarette, shown in dotted lines at 43, thereby pressing the remaining end of the cigarette over the opening 35 in the puffing device. This pressure will also cause contact 33 to engage spring 45 27 thus closing the circuit through resistance wire 31 which will cause ignition of the cigarette. At the same time the button 40 may be reciprocated as by the thumb of the same hand of the user to cause air to move to and fro in the cigarette 50 thereby bringing the same into full ignition when the cigarette may be freely picked off from the cradle for consumption.

To support the receptacle 10 as upon the dash 44 of an automobile, the bracket shown in Figure 55

4 at 45 may be utilized, which bracket is shown as made of an integral sheet of material comprising a plate 46, upstanding ears 47, and a downwardly projecting ear 48 provided with an opening 49 for passage of a thumb-screw 50 to secure the receptacle to the bracket by means of a stud screw 51 rigidly carried by a wall of the receptacle.

At the remaining end of the plate 46 there is shown an upturned portion 52 having a screw-threaded opening for reception of a clamping screw 53 to be applied in the well known manner.

The puffing device may be properly called an air pump and may if desired be made into a true pump by provision of a check valve over opening 35 and of a "cup leather" upon piston 38 as will be obvious.

Minor changes may be made in the physical embodiment of the invention within the scope 20 of the appended claims without departing from the spirit thereof.

I claim as my invention:

1. A lighter for cigarettes comprising, in combination: a support; a supporting cradle carried by said support; stop means rigidly carried by the support at one end of the cradle and having an opening; spring supported, electrical ignition means located adjacent the remaining end of the cradle and movable against an end of a

cigarette thereon to press the cigarette against said stop means at said opening; contact means in the path of movement of said ignition means; manually operated means to force air through said opening and the cigarette; and reciprocable 5 means to actuate said air forcing means operating substantially in the axis of movement of ignition means whereby one thereof may be actuated by a thumb and the other thereof by a finger of a single hand.

2. A lighter for cigarettes comprising, in combination: a support; a supporting cradle for a cigarette carried by said support; an electrical resistance ignition element spring supported upon said support at one end of said cradle and movable toward said cradle against resistance of its spring support; a pump cylinder formed with a closed end provided with a central opening, and rigidly supported at the remaining end of said cradle; a reciprocating piston in said cylinder; 20 operating buttons carried by the rod of said piston and by said ignition element respectively; said buttons simultaneously operable by a thumb and a finger respectively of one hand of a user; and contact means operable by movement of the 25 ignition element toward the cradle to energize said resistance element.

LOUIS V. ARONSON.
